US0D1060853S

(12) **United States Design Patent** (10) **Patent No.:** **US D1,060,853 S**
(45) **Date of Patent:** **** Feb. 4, 2025**

(54) **EXFOLIATOR CASE**

(71) Applicant: **Pacific World Corporation**, Irvine, CA (US)

(72) Inventors: **Seung Beom Bang**, Seoul (KR); **Diane Consalvi**, Corona, CA (US)

(73) Assignee: **PACIFIC WORLD CORPORATION**, Irvine, CA (US)

(**) Term: **15 Years**

(21) Appl. No.: **29/836,158**

(22) Filed: **Apr. 25, 2022**

(51) **LOC (15) Cl.** **28-03**

(52) **U.S. Cl.**

USPC **D28/76**

(58) **Field of Classification Search**

USPC D28/9, 73, 76, 77, 78, 83, 99; D9/600, D9/655, 658

CPC A45D 33/008; A45D 33/006; A45D 42/00; A45D 42/04; A45D 42/10; A45D 33/34

(57) **CLAIM**

The ornamental design for an “exfoliator case” as shown and described.

DESCRIPTION

FIG. 1 is a top rear perspective view of an exfoliator case showing our new design;

FIG. 2 is a bottom front perspective view thereof;

FIG. 3 is a rear end view thereof;

FIG. 4 is a front view thereof;

FIG. 5 is a right side view thereof;

FIG. 6 is a left side view thereof;

FIG. 7 is a top plan view thereof; and,

FIG. 8 is a bottom view thereof.

The broken lines shown in the drawings depict portions of the article that form no part of the claimed design.

1 Claim, 6 Drawing Sheets
